Primary Examiner — Mary Ann Calabrese*Assistant Examiner* — Jennifer L Rempfer(74) *Attorney, Agent, or Firm* — Venable LLP; Steven J. Schwarz(57) **CLAIM**

The ornamental design for a desk, as shown and described.

DESCRIPTION

FIG. 1 is a front-right perspective view of a desk according to the claimed design shown in a raised position;

FIG. 2 is a front view of the desk of FIG. 1;

FIG. 3 is a rear view of the desk of FIG. 1;

FIG. 4 is a left side view of the desk of FIG. 1;

FIG. 5 is a right side view of the desk of FIG. 1;

FIG. 6 is a top view of the desk of FIG. 1; and,
FIG. 7 is a front-right perspective view of the desk of FIG. 1 shown in a lowered position.

The features shown in broken lines represent portions of the desk which form no part of the claimed design.
